PICTURE HOOK

George A. Moore, Medford, Mass.

Application January 27, 1942, Serial No. 428,363

1 Claim. (Cl. 248—217)

This invention relates to hooks adapted to be secured to a wall or other support and to act as a support for pictures and other similar objects.

In hanging pictures a single hook is ordinarily employed, the picture wire being caught on the hook to support the picture. If the picture wire slips in the hook by reason of jarring of the wall or for any other cause, the picture tends to assume a slant which is unsightly. In order to correct this tendency on the part of the pictures, various devices have been contrived to prevent the picture wire from slipping through the hook. The present invention is an improved device of this sort which is characterized by simplicity, effectiveness and ease of manufacture.

According to the present invention, a piece of soft frictional material such as vulcanized rubber is secured in the hook where it will be engaged by the picture wire. The wire is thus gripped by the soft pad and is held against accidental longitudinal movement through the hook but is easily released from the hook if the picture is to be taken down.

For a more complete understanding of the invention, reference may be had to the following description of certain embodiments thereof, and to the drawing of which

Figure 1 is a perspective view of a picture hook before the insertion of a soft pad.

Figure 2 is a perspective view of a frictional pad adapted to be mounted in the hook shown in Figure 1.

Figure 3 is a front elevation of the assembled picture hook, but without the supporting nail.

Figure 4 is a section on the line 4—4 of Figure 3.

Figure 5 is a sectional view of a modified form of the invention.

Figure 6 is a sectional view of another modified form of the invention.

Figure 7 is a sectional view of still another form of the invention.

Figure 8 is a front elevation of the hook shown in Figure 7.

Figure 9 is a front elevation of another modification.

Figure 10 is a bottom plan view of the hook shown in Figure 9.

Referring to Figures 1 to 4 inclusive, the invention may be embodied in a picture hook comprising a strip of any suitable stiff material such as metal bent to shape as shown. The metal portion of the hook comprises a normally vertical rear portion 10, an upper portion 12 which

is bent into a triangular loop and is perforated in a manner well known in the art to receive a supporting nail or pin 14, and a lower portion 16 which is bent forward and upward so that it 5 extends at an acute angle from the lower end of the mid-portion 10. The lower portion 16 thus forms with the mid-portion 10 a V-shaped hook or open loop adapted to receive a picture wire or other strand for supporting the object which is to be hung on the hook. According to the invention, the portion 16 of the hook is provided with an inturned flange 18. Between the flange 18 and the lower end of the vertical portion 10 is located a pad 20 of soft frictional material such as soft vulcanized rubber. This pad is preferably formed for a crowded fit in the position indicated in Figure 4, against the inner face of the hook portion 16. If the pad is stretched somewhat so as to reduce its cross-sectional area as it is introduced into the space between the flange 18 and the back 10, and the tension is then released, the pad will tend to resume its normal cross-section and will thus bind tightly in the position shown. If desired, a suitable cement may be used to secure the pad in position, but this will not be necessary if the pad is properly fitted. As indicated in Figure 3, the pad is preferably made of such length that it will project slightly beyond the side edges of the metal portion of the hook.

The metal portion of the hook may be made of ordinary strip stock bent to shape as shown, or may be cast, molded or otherwise formed of metal or of any other suitable material such as 35 a synthetic resin or other plastic.

The frictional pads may be assembled with the hooks in any desired or convenient manner. If these pads are of soft vulcanized rubber, they may be made in the form of a continuous strip 40 molded to have a cross-section of suitable size and shape. A strip of such rubber may then be stretched to reduce its cross-section and a number of hooks may be placed thereon side by side and suitably spaced apart while the strip is in 45 stretched condition. The strip may then be released so as to permit the rubber to expand to approximately its normal cross-section, thus pressing tightly against the flanges 18 and the adjacent end portions of the backs 10. The strip is then severed between each pair of successive hooks, thus completing the operation of assembling.

Figure 5 illustrates a slightly modified form of the invention in which the lower portion 26 55 of the strip is bent or otherwise formed in such

a manner as to receive a pad 30 having a rectangular cross-section. This permits the use of a rubber strip of standard cross-section in place of the special shape shown in Figure 2.

In the forms of the invention shown in Figures 4 and 5, the frictional pad forms with the vertical portion 49 of the hook a V-channel in which the picture cord is adapted to jam and to be frictionally gripped by the pad 20. In figure 6, the V-channel is wholly in the friction pad 32 itself, the pad being fitted into the lower portion 36 of the hook which may be shaped as desired, a curved hook being illustrated in Figure 6. The extremity 38 of the strip is preferably flared outward to facilitate insertion of the picture cord in the hook.

In the form of picture hook shown in Figures 7 and 8, the lower portion of the strip is bent or otherwise formed to receive a pad 50 of substantially rectangular cross-section with a V-channel or groove 52 to receive the picture wire or cord 54. In this form the angle of the channel is wider than that shown in Figure 6 so that the picture wire is frictionally restrained from shifting but is not jammed in the angle. To receive the pad 50 the lower portion of the strip extends horizontally outward to form a bottom 55 and then vertically upward, the extremity being preferably flared outward as at 56 to guide the picture wire into the channel 52. The pad 50 may be longer than the width of the hook so as to project beyond the side edges of

the hook as indicated in Figure 8, the end portions of the pad being thus unsupported from below.

The hook shown in Figures 9 and 10 is substantially the same as that shown in Figure 8 except that the pad 50 is just long enough to extend from one side edge of the hook to the other without projecting beyond either edge. In this case it may be preferred to make the bottom 58 of the hook narrower than the rest of the hook, as shown in Figure 10, so that the end portions of the pad 50 are unsupported from below. When a picture is hung on the hook, the end portions of the pad yield somewhat to avoid sharp angles in the picture wire where it passes over the ends of the pads.

It is evident that various other forms and shapes of hooks may be employed to embody the invention without departing from the spirit or scope thereof as defined in the following claim.

I claim:

A picture hook comprising a strip of stiff material having a normally vertical mid-portion and a lower portion bent upward to make an acute angle with said mid-portion, an in-turned flange at the extremity of said lower portion of the strip, and a piece of relatively soft frictional material fitted against the inner face of said lower portion between said bend and the in-turned flange.

GEORGE A. MOORE.
